Filed Sept. 22, 1955, Ser. No. 535,862

11 Claims. (Cl. 137—73)

This invention relates to combined temperature and pressure fluid relief valves and more particularly to an improved valve which incorporates an externally accessible temperature relief plug or fuse while yet being of reduced size and weight and reduced cost of manufacture.

In the type of temperature-pressure relief valve to which the present invention relates, a valve housing defines an internal chamber which is divided into exhaust and pressure portions by a partition or web having a circular valve seat, and a spring holds a valve body against the seat to resist pressures below the predetermined limit for which the spring is set. A passage connects the pressure chamber portion to the exhaust chamber portion. This passage is plugged by a low fusion metal or other suitable heat responsive material so that when predetermined temperature limits are exceeded the plug melts or is released opening the passage between the chamber portions. Thus the exhaust chamber portion receives fluid released from the pressure chamber portion through either the circular seat of the pressure control system or the passage of the temperature control system.

One of the principal objects of this invention is to provide a relief valve of the character mentioned having a housing of generally cylindrical external contour and of materially reduced weight and cost of manufacture with a squared or parallel flat sided wrench receiving section or part so that the housing may be turned by a wrench. More specifically it is sought to provide a generally cylindrical contoured valve housing of relatively thin wall section having an integral internal reinforcing web in the vicinity of the lands of a wrench receiving portion to provide a valve of reduced weight and cost of manufacture which has sufficient strength in the vicinity of the wrench receiving section or lands to prevent collapsing of the housing walls by wrench applied pressures.

As an additional object of the invention the quantity of material required to form a temperature-pressure relief valve is reduced with attendant savings in weight and manufacturing cost due to the shortening of the length of the valve.

The provision of a generally cylindrically contoured housing having an enlarged wrench receiving section or part which has parallel wrench receiving surfaces or lands provides a valve which may be installed by an unskilled or uninstructed person without danger of damage to the valve. Such an unskilled person would only apply a wrench to the wrench receiving part. It is, therefore, a further object of the invention to provide a valve having a construction which will induce an operator to apply a wrench only to the strongest portion of the housing which portion is in the vicinity of the reinforcing web.

A further object of the invention is to provide a relief valve having the valve seat of the pressure relief structure in the plane of one or more of the attaching bosses to thereby reduce the overall length of the valve housing as well as to strengthen it.

2

A still further object of the invention is to provide a valve in which the threaded bosses for the fluid openings which are transverse to the housing axis overlap one another axially and also are located in the vicinity of the reinforcing web to strengthen the housing and increase its resistance to fracture. More specifically it is sought to provide increased housing strength by locating the hollow or tubular attaching bosses at different points along the length of the housing axis spaced less than the diameter or other transverse dimension of the smaller of such bosses so that such bosses overlap one another along the housing length although their axes are longitudinally spaced.

A still further object is to provide a combined temperature pressure relief valve in which the fusible plug constituting the temperature relief element is replaceable from the outside of the valve casing without removing the latter from its installed position and without disturbing or removing the pressure relief valve assembly. More particularly this aspect of the invention is concerned with the provision of an auxiliary or appendage boss integral with one of the fluid opening bosses, the auxiliary boss having an internal chamber connected to the pressure and exhaust chambers and adapted to receive the fusible sealing plug.

Further objects and advantages will be apparent from the following detailed description of a preferred embodiment representing the best mode of practicing the invention and from the appended drawings which are a part of the specification.

In the drawings:

Fig. 1 is a front elevational view of the relief valve partly in section and with parts broken away showing the cap or closure, the reinforcing web, the housing boss portions for receiving or attaching to inlet exhaust and outlet conduits, and the auxiliary boss containing the temperature relief plug;

Fig. 2 is a side elevational view partly in section and with parts broken away and removed, substantially as seen from the plane indicated by the line 2—2 of Fig. 1, showing the inlet and outlet openings, the pressure and exhaust chamber portions, the elements of the pressure relief assembly, and part of one of the lands of the wrench receiving portion;

Fig. 3 is a cross sectional view taken substantially along the line 3—3 of Fig. 2 showing the reinforcing web, the wrench receiving portion, the inlet opening, and the temperature relief assembly;

Fig. 4 is a rear elevational view of the complete valve showing the flat wrench land portions of the housing surrounding the internal reinforcing web; and

Fig. 5 is a bottom view of the valve showing the shape of the wrench receiving section.

The valve of the present invention as embodied in the structure shown in the drawings, representing the best known mode of practicing the invention, comprises a hollow chambered body or housing 1 formed as by machining or forging but preferably and more economically by casting brass, aluminum or other suitable metal. The internal chamber of the body housing is divided by an integral transverse web or partition 20 into a pressure chamber 2, shown beneath the partition, and an exhaust chamber 3, shown above the partition. It is understood, of course, that in suitable applications the valve may be inverted from the position shown in the drawings or used horizontally or in any other desired angular relationship to the other components of the fluid system. The part of the housing which defines the pressure chamber portion is formed with integral threaded tubular bosses the internal passages of which are continuous with the pressure chamber 2. The particular valve illustrated is intended for use with a conventional

hot water heater tank. Accordingly the lower end of the housing body is continuous with or in the form of an externally threaded coaxial attaching boss 11 which may be screwed into the internally threaded bunghole or outlet opening of a conventional water heater tank. On one side of the housing is an integral laterally projecting boss 8 having an internal passage 4 continuous with the pressure chamber 2, this passage constituting the outlet through which the hot water from the tank heater is supplied to the system protected by the relief valve. The boss 8 may be externally threaded, provided with a fitting to receive a union nut or, as shown, threaded 6 internally to receive the conventionally threaded end of a water distribution pipe.

Also projecting laterally from the housing body 1 but with its axis spaced axially along the axis of the housing body from the axis of the boss 8 a distance less than the diameter of the boss 8 (preferably about half such diameter) is an integral tubular boss 22 which defines an outlet passage 23 continuous with the exhaust chamber 3 above the partition 20. The axis of the exhaust boss 22 is rotated about 90 degrees about the housing axis relative to the axis of the outlet boss 8 so that the plane of the transverse partition 20, more specifically the plane of the valve seat formed in the partition, as will be later described, extends through the outlet passage 4 and also through the exhaust passage 23 in parallel relation to the axes of the bosses in which such passages are formed. Thus the plane of the reinforcing partition (and valve seat) lies within the outlet and exhaust passages with portions of each of such passages being disposed on opposite sides of the partition plane. By this arrangement maximum strength is imparted to the valve and it is better able to withstand the stresses to which it is subjected when pipes are screwed into the bosses 8 and 22 than in the case of a conventional valve.

The exhaust boss 22 may be internally threaded, as indicated at 18, to receive the threaded end of a suitable discharge conduit for carrying off any fluid released into the exhaust chamber 3 through the pressure relief passage in the partition 20 or through the drilled intersecting temperature relief passages.

A flanged cap 24 having a noncircular hex top and downwardly extending externally threaded portion 25 is inserted in threaded engagement with internal threads 26 which are formed inside a top opening of the housing which is continuous with the top of the exhaust chamber portion 3. The cap 24 forms a fluid seal for the exhaust chamber portion through coaction with washer 21 disposed between the cap flange and the upper end of the housing. A valve adjusting screw plug 27 having external threads 28 is placed in threaded engagement with the threaded section 26 of the housing, inwardly of the cap 24.

A valve seat 31 is formed in the central integral web or partition 20 which divides the housing interior into the upper exhaust and lower pressure portions mentioned. The valve seat defines a circular opening 32 which connects the housing chamber pressure and exhaust portions 2 and 3. A valve body indicated generally at 33 is held in yieldable sealing engagement against the valve seat 31 by a helical coil compression spring 29 reacting against the screw plug 27.

The valve adjusting screw plug has an annular relief area 34 on its under side which receives a circular spring receiving disc or seat member 35. The spring receiving member 35 is a shallow cup shaped brass stamping and on its under side is formed to define an annular relief 36 which receives and locates upper end 37 of the spring 29. The spring adjusting screw 27 has a frusto-conical pin extension 30 directed downwardly in the center of annular relief area 34 to provide point contact bearing in depressed center 38 of the disc 35, there being an annular clearance surrounding the pin 30 between the screw plug 27 and the spring receiving cup 35. The point contact so formed transmits axial biasing pressure between the spring 29 and

the spring adjustment screw 27 to reduce friction upon rotation of the plug 27 relative to the spring and spring receiving member 35. The point contact permits the valve body to be guided into complete and accurate engagement with the valve seat and prevents objectional internal stress or binding conditions which might otherwise exist.

The housing 1 is principally of cylindrical curvature externally, or substantially so, and inner surfaces 39, 40 define, respectively, the generally circular sectioned pressure and exhaust chamber portions 2 and 3. The pressure chamber portion 2 is defined by the inner surface 39 of circular section or having circular curvature substantially throughout its length from the bottom 12 of the housing to the partition 20. A suitable rotary tool may be introduced through the top end opening of the housing 1 and passed downwardly, axially through the exhaust chamber portion to machine a smooth cylindrical inner surface 40. The web or partition 20 has an upper surface which defines an annular channel 15 surrounding the valve seat 31. The channel 15 may be machined by the same rotary tool which machines the inner surface 40 to form the valve seat 31 in the same operation as the inner surface 40. The smooth inner surface 40 thus formed serves to guide the valve body 33 during axial movement when the valve is unseated in response to excessive pressure in the pressure chamber or seated in response to pressure exerted by the biasing spring 39.

The valve body 33 has an internally threaded axial passage 43 which receives the threaded reduced diameter section 45 of a plug member 44. Flanged end portion 46 of the plug has a pair of relieved areas or flats 47 to provide surfaces to receive a wrench or the like to tighten the threaded engagement of the plug and the valve body.

An annular flat faced washer 52 of rubber, polyethylene or other suitable plastic material is affixed to and forms a part of the valve body as by being clamped between the flat end face of the valve body 33 and the flange of the plug 44. This washer is positioned to engage the valve seat 31 in the provision of a fluid-tight seal.

When pressure exerted by fluid in the pressure chamber portion 2 exceeds a predetermined limit and the valve body 33 is unseated in response to such pressure, an annular opening is formed between the complementary surfaces of the valve seat and body. The opening so formed permits fluid to pass upwardly through the valve seat opening 32 into the exhaust chamber portion 3 and thence outwardly through the exhaust passage 23.

An escape passage releases fluid from the pressure chamber 2 into the exhaust chamber 3 when the temperature of the device exceeds a predetermined limit. Such escape passage comprises intersecting drill holes 41 and 42 communicating, respectively, with the pressure and exhaust chambers. The hole 41 is drilled into the chamber 2 in a direction normal to and intersecting the longitudinal axis of the body housing 1 through a supplemental boss 48 located in the angle between the exhaust passage boss 22 and the housing body. This supplemental boss 48 is integrally joined to both the body housing and the exhaust boss 22, being the same length as but narrower than the latter as shown in Figures 3 and 5. The passage 42 is formed by inserting a drill through the open top of the body housing 1, the axis of the drill being disposed at an angle such as about 20 degrees to and intersecting the axis of the body housing. The upper end of the drilled passage 42 thus opens into the exhaust chamber 3 adjacent and outside of the valve seat 31 of the pressure relief structure.

At the intersection of the passages 41, 42 an enlarged chamber is provided as by a counterbore 49 to receive a fuse plug 50. This plug is of cylindrical shape and comprises any suitable low melting point metal alloy such as the eutectic alloy of about the following composition:

52.5% Bi
32% Pb
15.5% Sn

having a melting point of about 203 degrees F. The outer end of the drilled through passage in the supplemental boss 48 is threaded to receive a cap screw 51 which bears axially against the fuse plug 50 to seat the inner end of the latter against a radial shoulder 53 at the inner end of the counterbore 49, thereby sealing the passage 41 from both the escape passage 42 and the tapped opening through the face of the boss 48. The screw 51 may be used to apply deforming pressure to the plug so that the latter is made to fill the counterbore and sealingly engage the walls.

Upon an increase in temperature of the fluid in the hot water tank or other system protected by the present valve above a predetermined temperature valve, such as the 203-degree F. temperature mentioned, such temperature being transmitted to the housing body 1 by conduction as through the threaded attaching boss 11, the temperature of the plug 50 is raised above its melting point and the plug is released through the escape passage 42, thereby clearing the intersecting passages for the escape of high pressure fluid from the pressure chamber 2 into the exhaust chamber 3. Without removing the housing body from its connection in the fluid system and without disturbing or disassembling the pressure relief assembly, to be later described, the temperature relief plug 50 can be readily replaced by simply removing the cap screw 57, inserting a new plug into the chamber 49 and reinserting the retaining cap screw. The present invention thus provides an external access fuse arrangement which simplifies service of the valve in use as well as original assembly. As an additional feature the location of the supplemental boss 48 in the angle between the laterally projecting exhaust boss 22 and the housing body 1 strengthens the entire valve structure.

Intermediate the ends of the housing there is formed a portion or section of generally squared configuration having cylindrically surfaced portions both above and below, in the provision of parallel wrench receiving surfaces or lands 56 and 57 and a flat surface 55 normal to the wrench lands. The wrench receiving section permits the generally cylindrically contoured valve to be rotated by a crescent or other suitable wrench.

The wrench land 55 is parallel to the plane of end face 59 of the threaded boss 8 so that a wide jawed wrench can be applied across the body 1 with one jaw of the wrench engaging the land 55. In general, the wrench receiving section of the housing body, comprising the flat lands 55, 56 and 57, is disposed between the plane of the valve seat 31 and one of the threaded attaching bosses, here the main attaching or inlet boss 11. A person installing or removing the valve is thus able to apply a wrench, other than a pipe wrench which is apt to mar or disfigure the valve, to the exterior of the valve to rotate the valve relative to the tank or other device with which the valve is associated.

To strengthen the housing walls the internal web 20 is located in the vicinity of the wrench receiving section and may even lie within the wrench lands. Preferably the lower or pressure chamber face 58 of the web 20 lies in a plane which is substantially normal to the axis of the housing 1 and to the planes of the wrench receiving surfaces 55, 56 and 57. A person installing a valve having web and wrench receiving portions thus located will, without instruction or supervision, normally apply a wrench to the strengthened and reinforced portion of the housing body rather than to one of the more collapsible end portions.

To provide a valve having a shortened longitudinal extent as well as to increase the strength of the housing, the boss 8 which defines the opening 4 is located so that the axis of such opening lies substantially in the plane of the web lower or pressure chamber face 58. Such location of the boss and the lateral passage or opening permits the reinforcing strength of the integral internal web 20 to give support to the housing walls at and adjacent

the lines of connection between the walls and the base of the boss. Thus the housing body is reinforced to resist wall collapsing pressures which may exist under wrench application. To close off the the exhaust chamber 3 from the outlet passage 4 the web 20 includes a vertical part 63 which extends longitudinally in the housing. This vertical or longitudinal web part 63 is cylindrically curved on that side which faces the exhaust chamber 3, such side having a face that coincides with the surface 40 of the exhaust chamber. The other face of the web part 63 which closes off the upper half of the passage 4 at its inner end may be flat, as shown. Communication between the opening 4 and the pressure chamber 2 is through semi-circular opening 64 which has a cross-sectional area substantially equal to the cross-sectional area of the fluid conducting passage of a conduit of size appropriate for connection to the boss 8. Thus, a valve of shortened axial length having an outlet opening or passage located in the vicinity of maximum wall strength is provided, while at the same time impedance of fluid flow is avoided.

A pressure-temperature relief valve having a short axial length housing, a generally cylindrical external contour, an improved wrench receiving part, an external access temperature responsive fuse and an internal reinforcing web appropriately positioned to provide reinforcing strength to resist wall collapsing pressures has thus been provided.

In accordance with the patent statutes the principles 30 of the present invention may be utilized in various ways, numerous modifications and alterations being contemplated, substitution of parts and changes in construction being resorted to as desired, it being understood that the embodiment shown in the drawings and described above 35 is given merely for purposes of explanation and illustration without intending to limit the scope of the claims to the specific details disclosed.

What I claim and desire to secure by Letters Patent of the United States is:

40 1. A fluid relief device comprising a hollow housing having internal pressure and exhaust chambers, means defining an opening between the chambers, a valve movable into and out of sealing relation to the opening, means biasing the valve normally to seal the opening and adapted to yield to a predetermined pressure differential 45 between the chambers to permit the flow of fluid from the pressure chamber to the exhaust chamber, the housing being formed with openings into the pressure chamber for association with supply and use conduits and formed with an opening into the exhaust chamber constituting an exhaust, the housing being formed with intersecting passages one of which communicates with the pressure chamber and another of which communicates with the exhaust chamber, a fusible and deformable plug disposed 50 in one of the intersecting passages, means engaging the plug to locate the latter in predetermined position in the passage in which it is received, said located plug extending across the intersection of the passages, and means actuatable to apply deforming pressure to the located 55 plug whereby the plug fills and sealingly engages the walls of the passage in which it is received on both sides of said intersection and to hold the located and deformed plug against the locating means.

2. A fluid relief device comprising a hollow housing having an internal partition dividing the housing interior into pressure and exhaust chambers, said partition being formed with an opening through which the pressure chamber communicates with the exhaust chamber, valve means normally sealing the opening in the partition, the housing being formed with integral bosses having passages 65 communicating with the pressure chamber, a supplemental boss projecting laterally from the housing body adjacent the partition, said supplemental boss being formed with internal intersecting passages one of which communicates with the pressure chamber and another of which com-

municates with the exhaust chamber, one of said passages being formed with a counterbore providing an annular shoulder located between the intersection of the passages and one of the chambers, a fusible plug disposed in the counterbore, said plug extending across the intersection of the passages, said laterally projecting supplemental boss being formed with an access passage having an external opening through which the plug is insertable into its position in the counterbore, and means receivable in the access opening to close the latter and retain the plug captive, said plug retaining means being actuatable to force the plug into intimate bearing relation to the shoulder around the entire circumferential extent of the latter whereby to seal the counterbored passage and to deform the plug into sealing engagement with the wall of the counterbore on both sides of the intersection.

3. A fluid relief device comprising a hollow housing having an internal partition dividing the housing interior into pressure and exhaust chambers, said partition being formed with an opening through which the pressure chamber communicates with the exhaust chamber, valve means normally sealing the opening in the partition, the housing being formed with integral bosses having passages communicating with the pressure chamber, a supplemental boss projecting laterally from the housing body adjacent the partition, said supplemental boss being formed with internal intersecting passages one of which communicates with the pressure chamber and another of which communicates with the exhaust chamber, one of said passages being formed with a counterbore providing an annular shoulder located between the intersection of the passages and one of the chambers, a substantially cylindrical deformable and fusible plug disposed in the counterbore, said plug being of greater length axially of the counterbored passage than diameter and than the distance from the shoulder across the intersection of the passages and of the same cross sectional shape as the counterbored passage at such intersection, and means in one of the passages biasing the plug against the shoulder to seal the counterbored passage at the shoulder and on both sides of the intersection and the passage which intersects the counterbored passage at the intersection.

4. A fluid relief device comprising a hollow housing having an internal partition dividing the housing interior into pressure and exhaust chambers, said partition being formed with an opening through which the pressure chamber communicates with the exhaust chamber, valve means normally sealing the opening in the partition, the housing being formed with integral bosses having passages communicating with the pressure chamber, a supplemental boss projecting laterally from the housing body adjacent the partition, said supplemental boss being formed with internal intersecting passages one of which communicates with the pressure chamber and another of which communicates with the exhaust chamber, one of said passages being formed with a counterbore providing an annular shoulder located between the intersection of the passages and one of the chambers, a substantially cylindrical deformable and fusible plug disposed in the counterbore, said plug being of greater length axially of the counterbored passage than diameter and than the distance from the shoulder across the intersection of the passages and of the same cross sectional shape as the counterbored passage at such intersection, and a screw threaded into the counterbored passage and actuatable to bear axially against the plug to hold the latter axially against the shoulder and on both sides of the intersection whereby to seal the counterbored passage at the shoulder and the passage which intersects the counterbored passage at the intersection.

5. In a fluid relief device of the type comprising a hollow housing, means in the housing dividing the interior into pressure and exhaust chambers and formed with a connecting opening between the chambers, a spring biased valve normally closing said opening and adapted to yield

to a predetermined pressure differential in allowing fluid to escape from the pressure chamber into the exhaust chamber, the housing being formed with a through passage extending from an outside opening to an inside opening into the pressure chamber, means providing an abutment in the passage, a fusible and deformable plug disposed in the passage in direct sealing contact with the passage wall, one end of the plug being disposed against the abutment, a screw threaded into the through passage, said screw being adapted upon tightening to bear against the other end of the plug in applying deforming pressure thereto to confine the plug between the abutment and the screw and to effect a seal between the plug and the walls of the passage, the housing being formed with a relief passage intersecting and having one end opening into the through passage adjacent the abutment at a point between such abutment and the screw so that said end opening of the relief passage is closed and sealed by the plug upon deformation of the latter by screw pressure,

20 and the other end of the relief passage being in communication with the exhaust chamber.

6. In a fluid relief device of the type comprising a hollow housing, means in the housing dividing the interior into pressure and exhaust chambers and formed with a connecting opening between the chambers, a spring biased valve normally closing said opening and adapted to yield to a predetermined pressure differential in allowing fluid to escape from the pressure chamber into the exhaust chamber, the housing being formed with a through passage extending from an outside opening to an inside opening into the pressure chamber, means providing an annular shoulder in the passage facing toward the outside opening, a fusible and deformable plug disposed in the passage and against the shoulder, a screw threaded into the passage from the outside end and adapted upon tightening to bear against the plug in applying deforming pressure thereto to force the plug against the shoulder in effecting a primary seal of the passage and against the surrounding wall of the passage adjacent the shoulder in effecting a secondary seal of the latter, the housing being formed with a relief passage intersecting and having one end opening into the through passage between and spaced from both the shoulder and the screw so that said end opening of the relief passage is closed and sealed by the plug upon deformation of the latter by screw pressure,

30 said plug also being in direct sealing engagement with the surrounding wall of the through passage between the relief passage opening and the screw, and the other end of the relief passage being in communication with the exhaust chamber.

7. A fluid control device comprising an elongated hollow metal housing having a threaded attaching end and an internal transverse partition dividing the housing interior into pressure and exhaust chambers respectively adjacent to and remote from the attaching end, the partition being formed with an opening through which the pressure chamber communicates with the exhaust chamber, a spring biased valve body normally sealing the partition opening, the housing having integral laterally projecting bosses each formed with a circular sectioned opening communicating with the housing interior, one such boss opening communicating with the pressure chamber, another such boss opening communicating with the exhaust chamber, the axes of said boss openings being disposed in spaced generally parallel planes normal to the longitudinal axis of the housing, said planes being intersected by the housing axis at points spaced along the latter a distance less than the diameter of either one of said boss openings, said partition being disposed substantially wholly between said parallel planes, the housing body being formed with external wrench receiving flats which extend onto a portion of the housing located between the limits of one of the bosses along the housing axis, at least two of the wrench flats being in oppositely disposed parallel relation, and one of said bosses having

a planar end face parallel to the housing axis and to another of the wrench flats for receiving the housing between opposed wrench jaws with one such jaw engaged against the end face of the one boss and the other such jaw engaged against the one flat.

8. A fluid control device as defined in claim 7 in which the axes of the boss openings are disposed in planes substantially normal to one another and one of the bosses is disposed wholly on one side of the plane of one of the wrench flats.

9. A fluid control device as defined in claim 7 in which the axes of the boss openings intersect the housing axis.

10. A fluid control device as defined in claim 9 in which the axes of the boss openings are disposed in planes substantially normal to one another.

11. A fluid control device as defined in claim 7 in which the attaching end is formed with a through passage on the housing axis continuous with the pressure chamber and the threads on the attaching end are con-

centric to the housing axis so that the device is attached to a threaded fitting by relative rotation about the housing axis.
